UNITED STATES PATENT OFFICE.

WILLIAM C. BUSH, OF WILMINGTON, DELAWARE.

GUN-CARTRIDGE.

SPECIFICATION forming part of Letters Patent No. 743,242, dated November 3, 1903.

Application filed April 29, 1903. Serial No. 154,865. (No model.)

To all whom it may concern:

Be it known that I, WILLIAM C. BUSH, a citizen of the United States, residing in Wilmington, Delaware, have invented certain Improvements in Gun-Cartridges, of which the following is a specification.

The object of my invention is to so construct the base-block of a cartridge-shell as to provide in a more effective manner than before for the gradual increase in the rate of combustion of the explosive charge at the beginning of said period of combustion. This object I attain in the manner hereinafter set forth, reference being had to the accompanying drawings, in which—

Figure 1 is a sectional view, on an enlarged scale, of a cartridge-shell constructed in accordance with my invention; and Fig. 2 is a similar view illustrating another form of my improved cartridge-shell.

1 represents the casing of the shell, and 2 the base-block at the breech of the same, this base-block having the usual recess 3 for the reception of the primer. The inner face of the breech-block presents a succession of steps 4, leading from the flame-opening to the shell 1, so as to provide at the base of the charged shell a mass of powder which gradually increases in bulk from the flame-opening onward, thereby causing a gradually-increasing development of power when the combustion of the charge begins. In the cartridge shown in Fig. 2 substantially the same effect is obtained by coiling a tapered strip of the material constituting the base-block so as to provide a spiral seat instead of the succession of parallel steps.

I am aware that it has been proposed to

provide a cartridge with a base-block having a conical opening therein; but in such case 40 the packing of the explosive into the shell causes a lateral forcing together of the particles contained in said conical opening, and this compacting of the explosive causes a more rapid combustion of the same and substantially neutralizes the effect of the cone 45 in producing a gradually-increasing rate of combustion due to the gradually-increasing bulk of the explosive. My improved base-block, however, while providing a substantially conical powder-chamber, presents a succession of shelves which are substantially at right angles to the axial line of the cartridge. Hence there is no wedge-like action, such as that of a straight-sided cone, and the 50 compacting of the particles of explosive at the base of the shell is prevented.

Having thus described my invention, I claim as new and desire to secure by Letters Patent—

1. A cartridge-shell having a base consisting of a series of steps forming a substantially conical powder-chamber, substantially as specified.

2. A cartridge-shell having a base presenting a continuous spiral ledge which surrounds a substantially conical powder-chamber, substantially as specified.

In testimony whereof I have signed my name to this specification in the presence of two subscribing witnesses.

WILLIAM C. BUSH.
